(57) **CLAIM**

The ornamental design for a gate beam, as shown and described.

DESCRIPTION

FIG. 1 is a first end perspective view of a gate beam in accordance with the design;

FIG. 2 is a second end perspective view thereof;

FIG. 3 is a top view thereof;

FIG. 4 is a bottom view thereof;

FIG. 5 is a first end view thereof;

FIG. 6 is a second end view thereof;

FIG. 7 is a first side elevation view thereof;

FIG. 8 is a second side elevation view thereof;

FIG. 9 is a second side environmental view showing the gate beam with a gate panel; and,

FIG. 10 is a top environmental view showing the gate beam with the gate panel of FIG. 9.

The drawings contain symbolic break lines illustrated as dash-dash lines in FIGS. 1-10. Any portion between the break lines forms no part of the claimed design. The broken

(Continued)

long dash-short dash lines in FIGS. 9 and 10 depict environment and form no part of the claimed design.

1 Claim, 8 Drawing Sheets**Related U.S. Application Data**

division of application No. 15/172,141, filed on Jun. 2, 2016, now Pat. No. 10,227,742.
